Des. 233,586

Patented Nov. 12, 1974

233,586

SCRAPER OR THE LIKE

Theodore J. Kopp, 9720 227th Place SE.,
Edmonds, Wash. 98020

Filed Sept. 17, 1973, Ser. No. 397,895

Term of patent 14 years

Int. Cl. D7—05

U.S. Cl. D7—181

Fig. 1

Fig. 5

Fig. 2

Fig. 3

Fig. 4

Fig. 6

Fig. 7

FIG. 1 is an isometric view of a scraper or the like, showing my new design;

FIG. 2 is a side elevational view thereof;

FIG. 3 is a top elevational view thereof;

FIG. 4 is a bottom elevational view thereof;

FIG. 5 is a view of one end thereof;

FIG. 6 is a view of the other end thereof; and

FIG. 7 is a lateral cross-sectional view thereof, taken substantially along line 7—7 of FIG. 2.

I claim:

The ornamental design for a scraper or the like, substantially as shown and described.
